Inventor

George R. Cudlipp,

By George G. Wells,

Attorney

UNITED STATES PATENT OFFICE.

GEORGE R. CUDLIPP, OF LOS ANGELES, CALIFORNIA.

TOY PISTOL.

Application filed September 5, 1922. Serial No. 586,345.

To all whom it may concern:

Be it known that I, GEORGE R. CUDLIPP, a subject of Great Britain, residing at Los Angeles, in the county of Los Angeles and State of California, have invented a certain new and useful Toy Pistol, of which the following is a specification.

My invention relates to toy pistols and consists of the novel features herein shown, 10 described and claimed.

Fig. 1 is a side elevation of a toy pistol embodying the principles of my invention, the pistol being loaded ready to fire and the movements in firing being shown in dotted 15 lines.

Fig. 2 is a top perspective of the bullet shown in Fig. 1.

Fig. 3 is a perspective of the bullet with the plane omitted.

20 Fig. 4 is a vertical cross section on the line 4-4 of Fig. 1 and looking in the direction of the arrows.

Fig. 5 is a horizontal cross section on the lines 5-5 of Figs. 1 and 4 and looking 25 downwardly.

Fig. 6 is a perspective of the spring wire bullet retainer and triggers shown in Figs. 1 and 4.

Broadly, my toy pistol consists of a handle 30 1, a barrel 2, a spring wire bullet retainer and triggers 3, a bullet 4, and an expansion spring bullet projector 5.

The handle 1 is a block of wood about half an inch thick and three inches long when 35 seen edgewise as in Fig. 4 and about an inch wide when seen sidewise as in Fig. 1.

The barrel 2 is a straight solid wire about one-eighth by five or six inches and the wire is driven firmly into the handle 1 from its 40 forward edge and near its upper end, and so that when the barrel is horizontal the handle is slightly inclined forwardly from the bottom, and the handle is cut so that the upper and lower faces 6 and 7 of the handle 45 are substantially parallel with the barrel 2.

The bullet retainer and triggers 3 are made of a single piece of spring wire about fourteen gage, and the wire consists of the anchor portion 8, the extension portion 9 substantially in line with the portion 8, the bullet retainer portion 10 extending upwardly from the forward end of the portion 9, the trigger portion 11 extending forwardly and downwardly from the upper end 50 of the portion 10, the return bend portion 12 at the forward end of the portion 11, the

trigger portion 13 extending from the other end of the portion 12 parallel with the portion 11, the retainer portion 14 extending from the portion 13 parallel with the portion 10, the extension portion 15 extending from the portion 14 parallel with the portion 9, the coil spring portion 16 extending from the portion 15 around the portion 9, the second trigger portion 17 extending from the portion 16, and the bearing portion 18 extending from the portion 17. The anchor portion 8 is firmly seated in the handle 1 just below the barrel 2 with the coil 16 against the front edge of the handle 1, and the retainer portions 10 and 14 normally press upwardly against the barrel. The bearing portion 18 presses against the front face of the handle 1 near its lower end and is held slidingly in place by a 75 staple 19.

The bullet 4 consists of a wooden ball 20 having a central opening 21 to receive the barrel 2 and having a flat side 22, the plane 23 fitting the flat side and the staple 24 holding the plane to the ball. The plane 23 is cut to simulate a flying machine.

The projecting spring 5 is a straight coil fitting loosely upon the barrel 2 and the rear end of the spring is secured through the 85 spring 16 to hold the spring 5 upon the barrel with its forward end free.

The bullet 4 is forced upon the barrel 2 from its forward end against the expanded spring 5 until the bullet engages the portions 11 and 13, and continued backward movement of the bullet presses the retainers 10 and 14 downwardly until the bullet passes the retainers and then the retainers spring upwardly in front of the bullet and hold 95 the bullet against the tension of the spring 5 and ready to fire.

The pistol is gripped in the ordinary way with the index finger upon the trigger portions 11 and 13 and the other fingers around 100 the handle and the second trigger 17. Pressure upon either trigger will release the bullet and the spring 5 will project the bullet 4.

The plane 23 may be omitted and the ball 105 20 left round if desired, and the second trigger 17 may be omitted.

The toy pistol thus constructed is amusing and instructive to children, is inexpensive, uses no dangerous and explosive explosive, and is harmless.

Various changes may be made without de-

parting from the spirit of my invention as claimed.

I claim:

1. A toy pistol comprising a block of wood forming a handle; a wire driven into the handle and forming a barrel; a wooden ball having a central opening to receive the barrel and forming a bullet; and a bullet retainer and trigger formed of a single piece of spring wire consisting of an anchor portion seated in the handle below the barrel, a first extension portion in line with the anchor portion, a first bullet retainer portion extending upwardly from the forward end of the extension portion, a first trigger portion extending forwardly and downwardly from the upper end of the first retainer portion, a return bend portion at the forward end of the first trigger portion, a second trigger portion extending from the other end of the return bend portion and parallel with the first trigger portion, a second retainer portion extending from the second trigger portion parallel with the first retainer, a second extension portion extending from the second retainer portion parallel with the first extension portion, a coil spring portion extending from the second extension portion around the first extension portion, and means connecting the coil spring portion to the handle, the coil spring fitting against the handle and the retainer portions normally pressing upwardly against the barrel. 40 45 50 55 60 65
2. A toy pistol comprising a block of wood forming a handle; a wire driven into the handle and forming a barrel; a wooden ball

having a central opening to receive the barrel and forming a bullet; and a bullet retainer and trigger formed of a single piece of spring wire consisting of an anchor portion seated in the handle below the barrel, a first extension portion in line with the anchor portion, a first bullet retainer portion extending upwardly from the forward end of the extension portion, a first trigger portion extending forwardly and downwardly from the upper end of the first retainer portion, a return bend portion at the forward end of the first trigger portion, a second trigger portion extending from the other end of the return bend portion and parallel with the first trigger portion, a second retainer portion extending from the second trigger portion parallel with the first retainer, a second extension portion extending from the second retainer portion parallel with the first extension portion, a coil spring portion extending from the second extension portion around the first extension portion, a portion for a second trigger extending from the coil spring portion, and a bearing portion extending from the second trigger; the coil spring fitting against the handle, the retainer portions normally pressing upwardly against the handle, and the bearing portion fitting slidingly against the lower end of the handle; and a staple inserted into the barrel and holding the bearing portion in place. 70

In testimony whereof I have signed my name to this specification.

GEORGE R. CUDLIPP.
